UNITED STATES PATENT OFFICE.

NEAL TRIMBLE MCKEE, OF YONKERS, NEW YORK, ASSIGNOR TO LOCOMOTIVE SUPER-HEATER COMPANY, OF NEW YORK, N. Y., A CORPORATION OF DELAWARE.

DAMPER.

1,225,986.

Specification of Letters Patent. Patented May 15, 1917.

Application filed March 22, 1916. Serial No. 86,034.

To all whom it may concern:

Be it known that I, NEAL TRIMBLE MCKEE, a citizen of the United States, residing at Yonkers, county of Westchester, State of New York, have invented certain new and useful Improvements in Dampers, of which the following is a full and accurate description, such as is required by the statute.

My invention relates to dampers, and more particularly to dampers used in connection with locomotives equipped with smoke tube superheaters.

In locomotives equipped with such superheaters it has become practically standard usage to arrange the superheater units in enlarged flues in the upper portion of the boiler, the unit ends being attached to a header located in the upper portion of the smokebox. To protect the units from injury by the hot gases from the firebox at times when no steam is circulating through them, a damper is arranged in the smokebox which automatically operates to shut off the flow of the heating gases through the enlarged flues at times when no steam is being supplied to the cylinders, and to permit such flow at other times.

It is a wellknown fact that when such locomotives work under varying conditions the temperature of the steam fluctuates; and it is the object of the present invention to decrease such fluctuations.

The nature of my invention will be better understood by referring to the drawings forming part of this specification, in which Figure 1 represents, partly in elevation and partly in section, a portion of a locomotive equipped with my invention; Fig. 2 showing a similar view of a modification.

Referring first to the form illustrated in Fig. 1, it will be seen that the usual and wellknown elements are present. The ends of the superheater units 1 are secured in the usual or any preferred way to the header 2, to which steam is supplied by the dry pipe 3, and from which it is carried by the steam pipe 4 to the cylinders of the locomotive. The heating gases, coming through flues, or smoke tubes, 5, pass through the opening 6 controlled by damper 6, and leave by way of stack 7. With damper 6 in closed position the flow of heating gases through the flues 5 is stopped. The operation of the damper 6 is automatic. When the main throttle is open steam from pipe 4, or some other pre-

ferred point between the throttle and the cylinder is carried by pipe 24 to cylinder 25 where it moves piston 26 to the left, the motion being transmitted by means of bell crank 27 and link 28 to the weighted link 29, which being keyed to the damper shaft rotates and opens the damper. When the throttle is closed and no steam pressure exists in pipe 4, the weight 30 closes the damper moving the piston 26 to the right into the position shown. This is a well-known arrangement and no claims are made to this part of the apparatus, except as it may enter into the combinations claimed.

A second damper 8, keyed to shaft 9, may oscillate between the positions shown in full and dotted lines respectively. The shaft 9 has keyed to it an arm, 17. Lever arms 15 and 13 are keyed to the shaft 14 forming with it a bell crank. Link 16 operatively connects arms 17 and 15. A slot in the arm 13 engages pin 12. This pin is fixed on the spindle 20 which carries at its upper end the plunger 10 and at its lower end plunger 19. Plunger 10 reciprocates in a portion of the steam pipe 4, while plunger 19 reciprocates in the dashpot 18. Spring 11, bearing against collar 31, which is secured to rod 20 by pin 32, opposes the downward movement of spindle 20. Shafts 9 and 14 preferably extend through the wall of the smoke box, so that arms 15 and 17, and the link 16 connecting them, lie outside of the smoke box.

The action of the device is as follows: When the main throttle is opened, the steam passing through steam pipe 4 will tend to depress the plunger 10. This depression is resisted by spring 11, and the actual position of plunger 10 will depend on the amount of steam flow at any given time. It will be evident that the position of the plunger 10 determines the position of damper 8. At the time of maximum steam flow damper 8 will be in the position indicated in dotted lines; at times of no flow, in the full line position; and at other times in intermediate positions. Dashpot 18 and its piston 19 serve to steady the action.

The result of such an arrangement is that as the steam demand increases, the flow of hot gases through the fire tubes 21 becomes freer, a smaller proportion of the total flow of gases occurs through flues 5; and thus, with the parts properly proportioned, the rate of evaporation increases

with an increased steam demand, while the temperature to which the steam is superheated remains substantially constant.

In Fig. 2 is illustrated a form of the invention wherein the control of the damper 8 is not automatic. Different positions can here be given to the damper 8 by means of the hand lever 22 located in the cab. This lever actuates the arm 17 through the reach 10 rod 23. The arm 17 is here also keyed to the shaft 9 and thus damper 8, also secured to shaft 9, is given its various positions by manipulation of the lever 22. The lever is latched in the wellknown way when it has 15 been put into the position desired.

With the apparatus in this form the engineer throws the lever 22 forward a distance proportionate to the steam demand, thus securing the same effect manually as is 20 obtained automatically in the form first described.

Manifestly certain variations are possible. Thus the position of the damper 8 may be thermostatically controlled, opening more 25 with an increase in the temperature of the steam; the damper may be given other shapes, or may be made to shut off completely the flow of hot gases through some 30 of the fire tubes at the periods of low steam demand. These and similar variations are evidently within the spirit of the appended claims.

I claim:

1. In a boiler of the class described, the 35 combination of flues, superheater elements located in said flues, fire tubes, and means to increase with an increased steam demand the proportionate part of the hot gases flowing through the fire tubes.

2. In a boiler of the class described, the 40 combination of flues, fire tubes, a steam pipe delivering steam from the boiler, superheater elements located in said flues, means for controlling the flow of hot gases through the flues, and means responsive to the flow of 45 steam through said steam pipe permitting an increased proportionate flow of hot gases through the fire tubes as the steam flow increases.

3. In a boiler of the class described, the 50 combination of flues, a superheater whose elements are located in said flues, a pipe to carry steam from the superheater, fire tubes, a baffle adapted to prevent gases from the fire tubes, from reaching the superheater 55 elements and to shut off the flow of hot gases through the flues, a damper in said baffle opening to its full extent in response to steam pressure in the steam pipe, and a damper adapted to permit a freer flow of 60 hot gases through the fire tubes with an increase in steam demand, but never shutting said flow off completely.

4. In a boiler of the class described, the 65 combination of flues, a superheater whose elements lie within said flues, a conduit carrying steam from the boiler to said superheater, a throttle in said conduit, a damper controlling the flow of hot gases through the flues, damper rigging which opens the 70 damper to its full extent, when the throttle is opened, and keeps it open until the throttle is again closed, fire tubes, a second damper controlling the flow of hot gases through said fire tubes, mechanism adapted 75 to open the second damper to a greater or lesser extent.

NEAL TRIMBLE McKEE.
